UNITED STATES PATENT OFFICE.

WILLIAM E. FRANK, OF ST. LOUIS, MISSOURI, ASSIGNEE TO FOSTER BROTHERS MANUFACTURING COMPANY, OF ST. LOUIS, MISSOURI, A CORPORATION OF MISSOURI.

DAY BED.

Application filed December 1, 1922. Serial No. 604,840.

To all whom it may concern:

Be it known that I, WILLIAM E. FRANK, a citizen of the United States, residing at St. Louis, Missouri, have invented a certain new and useful Improvement in Day Beds, of which the following is a full, clear, and exact description, such as will enable others skilled in the art to which it appertains to make and use the same.

10 This invention relates to day beds, and has for its main object to provide a day bed of novel construction that can be opened and closed easily and without the necessity of manipulating a device to raise 15 and lower the mattress supporting means of the extensible section of the bed, as is necessary with many of the day beds now on the market.

Another object is to provide a day bed 20 of the type which is so constructed that the springs used to assist in the movement of the extensible section will not exert pressure on either section of the bed in such a way as to tend to tilt or cock up said sections, thereby producing a day bed in which the legs of both sections will bear squarely and evenly on the floor when the bed is open, and the extensible section will assume a perfectly horizontal position and will 25 bear evenly on the stationary section when the bed is closed. Other objects and desirable features of my invention will be hereinafter pointed out.

Figure 1 of the drawings is a perspective 30 view of a day bed constructed in accordance with my invention, showing the bed open, a portion of one of the end pieces being broken away so as to more clearly illustrate the construction of the operating mechanism for the extensible section; and

Figure 2 is an end view of the bed, partly broken away, showing the bed closed, namely, with the extensible section superimposed upon the stationary section.

45 Referring to the drawings which illustrate the preferred form of my invention, A designates the two end pieces of my improved day bed, B designates the stationary section of the bed and C designates the extensible section, the end pieces A being of any preferred design and being connected in any suitable way to the stationary section B, as, for example, by means of headed pins 1 on the ends of said stationary section that fit in slotted plates on said end

pieces A. Each of the sections B and C of the bed is provided with a mattress supporting means, not shown, which may consist of coiled springs, a woven wire fabric or a linked structure, and each of said sections comprises a rigid frame which may be of any preferred construction. In the bed herein illustrated the frame of the stationary section B is provided with upwardly-projecting end members 2 whose top portions extend transversely of the end pieces A of the bed and the frame of the extensible section C is also provided with upwardly-projecting end members 3 which are so arranged with relation to the end members 2 of the stationary section B that they will be in longitudinal alignment with same when the bed is open and will be in vertical alignment with said end members 2 when the bed is closed. When the bed is closed, as shown in Figure 2, the extensible section C is arranged in superimposed relation with the stationary section B and is supported firmly by the end members 2 of said stationary section, and when the bed is open, as shown in Figure 1, the extensible section is positioned in front of the stationary section and lies in the same horizontal plane as said stationary section.

The operating mechanism for moving the extensible section C into and out of superimposed relation with the stationary section B is composed preferably of two swinging guide links 4 carried by the stationary section and having their upper ends pivotally connected at 5 to the end members 3 of the extensible section, two rockable actuating levers 6 carried by the stationary section and having their upper ends pivotally connected at 7 to the ends of said extensible section, and two contractile springs 8 connected at their rear ends to the upwardly-projecting end members 2 of the stationary section and connected at their front ends to cranks or angularly-disposed arms 9 on the actuating levers 6. The guide links 4 are preferably integrally connected to a horizontally-disposed rock shaft 4^a that is journaled in bearings 4^b arranged on the underside of the frame of the stationary section B, and said links are of such length that when the extensible section is closed, as shown in Figure 2, they will be arranged in a rearwardly-inclined position, and when said extensible section is open, as shown in

Figure 1, they will be arranged in a forwardly-inclined position. The actuating levers 6 are pivotally mounted on the stationary section B at points in front of and 5 in a higher horizontal plane than the pivotal connections between the stationary section and the lower ends of the guide links 4, and the upper ends of said actuating levers 6 are pivotally connected to the extensible section B at points in front of and 10 in a lower horizontal plane than the pivotal connections 5 between the upper ends of the guide links 4 and the extensible section C of the bed. While it is immaterial 15 how the actuating levers 6 are mounted on the stationary section B, I prefer to provide each of said levers with a horizontally-disposed portion, designated by the reference character 6^a in Figure 1, that is journaled 20 in a pair of spaced bearing members 10 on the stationary section B, thereby insuring a free and even movement of the levers 6. The purpose of connecting the guide links 4 together by a rock shaft 4^a is 25 to insure said links moving in unison, and thus prevent the operating mechanism of the extensible section from binding in the event the person who is opening or closing the bed grasps the extensible section C 30 adjacent one end of same instead of at the middle.

When the bed is closed the springs 8 are under tension. Consequently, all that is required to open the bed is to exert a slight 35 upward pull on the front end of the extensible section C, so as to permit the springs 8 to exert a pull on the crank arms 9 of the actuating levers 6, in a direction to cause said levers to rock upwardly and forwardly, and thus move the section C forwardly 40 and downwardly into its open position in front of the stationary section B. During this movement of the section C, the links 4 guide said section and hold it in a substantially horizontal position, and when the 45 actuating levers 6 are rocking into their forwardly inclined position, the crank arms 9 on said levers travel past center, and thus restore the tension on the springs 8, there- 50 by causing said springs to be in readiness to swing the levers 6 rearwardly when the front side of the extensible section is lifted during the operation of moving said extensible section into its closed position. 55 When the section C is in its open position, the front side of said section is sustained by legs 11 thereon and the rear side of said section is sustained by the upwardly-projecting end members 2 on the stationary section 60 against which the rear ends of the upwardly-projecting end members 3 of the extensible section C bear, the guide links 4 and the actuating levers 6 being so proportioned and arranged that after the extensible section has reached its open posi- 65

tion, it will be impossible for said section to move forwardly out of abutting engagement with the end members 2 of the stationary section B. In order that the end members 3 will clear the end members 2 during 70 the operation of moving the extensible section C into and out of its closed position, the members 3 of said extensible section are cut away at their rear ends or provided with inclined rear ends 3^a, as shown in Figure 2. 75 Preferably, the stationary section B is mounted on the end pieces A of the bed in such a manner that the legs 11 at the front side of the extensible section C will extend substantially flush with the front sides of 80 the end pieces A when said extensible section is in its closed position, as shown in Figure 2.

Owing to the fact that the guide links 4 are pivotally connected to the stationary section B at points below and to the rear of the axis of movement of the rock levers 6 and are pivotally connected to the extensible section C at points above and to the rear of the pivotal connections between the rock 90 levers 6 and the section C, there is no tendency for the sections B and C to cock up or assume a slightly angular position relatively to each other, either when the bed is open or when it is closed. When the bed 95 is closed, the links 4 exert a downward pull on the rear ends of the members 3 of the extensible section, thus holding said extensible section firmly down upon the stationary section B, and when the bed is 100 open, the links 4 also exert a downward pull on the members 3 and prevent the rear ends of said members from moving upwardly relatively to the end members 2 of the stationary section B against which they abut. In fact, it is impossible to raise the rear side of the extensible section when said section is in either its closed position or open position without first lifting the front side of said section, due to the fact that the 105 links 4 counteract the tendency of the springs 8 to rock the levers 6.

A day bed of the construction above described has many features that make it a decided improvement on the various types 110 and kinds of day beds now on the market:

1st. It is not equipped with a lever or other actuating device that has to be operated to raise and lower the mattress supporting means of the extensible section during the operation of opening and closing the bed;

2nd. It is composed of only a few rugged parts of simple design that can be manufactured at a low cost and which are not apt to get out of order when the bed is in use;

3rd. The extensible section is mounted in such a way that it can be moved into and out of its closed position by a very slight 115

upward pressure applied to the front side of the extensible section at any point along the entire length of same; and

4th. It is equipped with a spring-actuated operating mechanism for the extensible section which is of such construction that there is no tendency for the two sections of the bed to assume a slightly angular position with relation to each other when the bed is open or when it is closed, thereby producing a day bed in which both sections of same will rest squarely on the floor when the bed is open, and the extensible section will assume a perfectly horizontal position 10 and bear evenly upon the stationary section when the bed is closed.

Having thus described my invention, what I claim as new and desire to secure by Letters Patent is:

20 1. A day bed, comprising a stationary section, an extensible section adapted to be arranged in superimposed relation with said stationary section when the bed is closed and in an extended position in front of said stationary section when the bed is open, rock levers on said stationary section pivotally connected to said extensible section for moving the same into and out of its extended position, and guide links 25 pivotally connected to said stationary section at points below the axis of movement of said rock levers and pivotally connected to said extensible section at points above the pivotal connections between said levers and 30 extensible section.

2. A day bed, comprising a stationary section, an extensible section adapted to be arranged in superimposed relation with said stationary section when the bed is closed and in an extended position in front of said stationary section when the bed is open, rock levers on said stationary section pivotally connected to said extensible section for moving the same into and out of 40 its extended position, and guide links pivotally connected at their lower ends to the stationary section at points below and to the rear of the axis of movement of said rock levers and pivotally connected at their 45 upper ends to said extensible section at points above and to the rear of the pivotal connections between said rock levers and extensible section.

3. A day bed, comprising a stationary section, an extensible section adapted to be arranged above said stationary section when the bed is closed and in front of said stationary section when the bed is open, rock levers on said stationary section pivotally 55 connected at their upper ends to said extensible section, actuating springs connected

at one end to said levers and at their opposite ends to said stationary section in such a way that they are normally under tension, and guide links pivotally connected to said stationary section at points below the axis of movement of said rock levers and pivotally connected to said extensible section at points above the pivotal connection between said levers and extensible section 60 for overcoming the tendency of said sections to assume an angular position relatively to each other when the bed is open or when it is closed, due to the force exerted by said springs. 70

4. A day bed, comprising a stationary section, an extensible section that is arranged above said stationary section when the bed is closed, rock levers on said stationary section pivotally connected at their upper ends to said extensible section, cranks associated with said levers, contractile springs connected to said cranks and to the stationary section in such a way that they are normally under tension, guide links 65 pivotally connected to said stationary section at points below and to the rear of the axis of movement of said levers and pivotally connected at their upper ends to said extensible section at points above and 70 to the rear of the pivotal connections between said rock levers and extensible section so as to overcome the tendency of said springs to cause the extensible section to cock up when the bed is open and when it 75 is closed, and means for rigidly connecting said links together so as to cause them to operate in unison.

5. A day bed having a stationary section that comprises a frame provided with upwardly-projecting end members, an extensible section adapted to be arranged in superimposed relation with said stationary section and comprising a frame provided with upwardly-projecting end members, 100 rock levers on said stationary section provided at their lower ends with crank arms and having their upper ends pivotally connected to said extensible section, contractile springs connected to said crank arms and to the end members of said stationary section, guide links pivotally connected at their lower ends to the stationary section at points below and to the rear of the axis of movement of said rock levers and having their 105 upper ends pivotally connected to the end members of said extensible section at points above and to the rear of the pivotal connections between said rock levers and extensible section, and means for causing said 110 guide links to move in unison. 115
